NECKTIE

Reuben E. Serrano, Los Angeles, Calif.

Application August 22, 1933, Serial No. 686,287

3 Claims. (Cl. 2—151)

This invention relates to neckties, and same has particular reference to ties of the bow type, an object of the invention being to provide a plurality of relatively independent parts, including a 5 bow-forming part and a co-operable knot-forming part, each designed and constructed so that one thereof may be easily interrelated with the other and the two connected to a neckband in a manner to enable the user to remove the bow-forming part when desired, such as when soiled, 10 and to quickly and conveniently substitute a new one therefor.

Another object of the invention is to provide a necktie in which the several structural parts employed will unite or combine to provide effective means for securely holding the bow-forming part against movement circumferentially of the neckband.

Another object of the invention is to provide co-acting structural parts which will satisfactorily serve to give strength and body to the bow-forming part to such extent as to hold the said part in a neat and pleasing position when worn.

Another object of the invention is to construct 25 a necktie from several pieces of material, the form and design of each of which is such that said pieces can be readily and perfectly formed into a tie, the general appearance of which will be more nearly like a ready-made tie.

Another object of the invention is to construct 30 a necktie from several pieces of material wherein one thereof will function to produce a more perfect knot than can be formed when the tie is constructed of a single piece of material, and which will function also to maintain a more symmetrical condition of the wing ends of the tie.

Other objects and advantages will become apparent as the description proceeds.

In the accompanying drawing,

Figure 1 is a view in front elevation of my improved tie;

Figure 2 is a view in rear elevation thereof;

Figure 3 is an elevation of the bow-forming part;

Figure 4 is a view in elevation of the neckband, with parts broken away;

Figure 5 is a view in elevation of the knot-forming part;

Figure 6 is a section on line 6—6 of Figure 2;

Figure 7 is a section on line 7—7 of Figure 2.

In theatrical or motion picture work, where the actors must work quickly and always present a neat and well-groomed appearance, it is necessary that they resort quite frequently to a change 55 of neckwear, in order, particularly in motion pic-

ture work, that soiled and untidy conditions shall not be at any time visible to the eye in the finished picture. Character actors find it necessary to make many changes of neckwear in the course of making motion pictures because of the grease 5 which is contained in the make-up, the same sooner or later coming in contact with the necktie, particularly the bow part thereof, prematurely soiling same, and this condition, if not corrected, 10 will detract very materially from the fine character of the finished picture. It is these difficulties in the use of previously existing ties that I wish to overcome, at the same time providing a new combination of elements in which the bow-forming part thereof may be conveniently and 15 quickly discarded and a new and clean part of similar construction substituted therefor, thus avoiding the necessity of discarding the whole of the tie. I have also endeavored to so combine the respective parts of the device employed that 20 when they are made up the article will have the same general appearance as a pre-made bow tie.

In practice I use a neckband 5, a knot-forming part 6, and a bow-forming part 7, each of which parts is preferably constructed of material of the same kind, and this may consist of silk of a texture to give body and a degree of stiffness to the made-up article. The bow-forming part consists of two identical pieces of material and as illustrated in Figure 6 the marginal edges of 25 one of said plies are turned in and sewed against the corresponding turned-in marginal edges of the mating piece of material, as at 8, whereby to give marginal stiffness to the bow and prevent sagging of the wings 9 thereof when the article 30 is worn. The wings 9 of this bow-forming part are substantially of diamond configuration, and the medial portion of this bow is reduced as at 10, the width of which is preferably less than the width of the neckband 5 and slightly greater 35 than the width of the knot-forming part. The knot-forming part 6 is formed of a single piece of material folded on itself along the line 11 and the folds thereof sewed together at the longitudinal edges 12 and across the ends 13. The 40 said knot-forming part is of uniform width throughout and in practice I find that the width of this part should be slightly less than the width of the reduced portion 10 of the bow-forming part. The neckband 5 is constructed in a manner 45 very similar to the method employed when producing the knot-forming part. This neckband is of uniform width throughout and is preferably wider than the aforesaid knot-forming part, whereby when the bow-forming part is po- 50 55

sitioned flatwise against the neckband preparatory to attaching same to said neckband, the longitudinal edges of said neckband will extend for a slight distance beyond the opposite edges 5 of the reduced portion 10 of the knot-forming part. It follows therefrom that when the knot-forming material is tied into a knot, as shown in Figures 1 and 2, the marginal edges of the neckband will be folded over against the opposite sides of the bow-forming part at said reduced portion 10 of the knot-forming part, whereby to give longitudinal stiffness to the body structure of the bow-forming part, so as to cause the wings 9 thereof to occupy their intended 10 symmetrical positions when the article is worn.

The knot-forming part 6 is of less length than the bow-forming part, so that when same is tied into a knot the ends 13 thereof will not under any circumstances be visible to the eye from the 15 front of the tie.

After the bow-forming part 7 has been placed flatwise against the neckband 5 so that the reduced portion 10 thereof occupies a position medially between the ends of the neckband, the 20 knot-forming part is placed in a position at right angles to the bow-forming part so as to traverse the front thereof. It is then firmly passed over the reduced portion 10 so that its ends will be brought behind the neckband, at which time said 25 knot-forming part is tied to produce a rather tight knot 14. In doing this, the edge portions of the neckband adjacent the reduced portion 10 of the bow-forming part will be curved backwards and slightly folded on itself. This causes 30 the neckband and the medial portion 10 of the bow-forming part 7 to assume a curved condition, as shown in Figure 7, thus giving considerable longitudinal rigidity to said bow-forming part at the opposite sides of said knot. When 35 the knot-forming part 6 is tied as just described, the free ends thereof adapt themselves to the adjacent curved surfaces of the neckband, and said ends are wholly concealed behind said band, so as not to be visible to the eye from in front 40 of the bow-forming part. One end of the neckband is provided with a buckle 15 of any conventional form which is adapted to adjustably receive the free end 16 of said band.

It follows from the construction set forth that 45 50 should the bow-forming part become soiled it may be readily removed and a new one substituted therefor, at slight cost.

What is claimed is:

1. A necktie consisting of a bow forming part; 55 a neckband forming part; and a knot-forming part; each of said parts comprising a plurality of plies of fabric material, the bow-forming part having end wings and a reduced connecting portion therebetween; the said knot forming part 60 being of uniform width throughout and less than that of the said connecting portion and of less length than the bow forming part and of less

width than the neck band forming part; the neck band forming part being of greater width than said connecting portion and adapted to be disposed in a longitudinal flatwise position in back thereof with its medial portion co-incident with the said connecting portion; the said knot forming part adapted to be placed flatwise in front of the aforesaid connecting portion and at right angles thereto and the ends thereof adapted to be passed over the upper and lower 10 edges of said connecting portion and the corresponding edges of the medial portion of the neck band forming part and knotted in back of the latter so as to transversely curve said connecting portion of the said bow-forming part and said 15 medial portion of the neck band forming part and to coact with the multi-ply structures of these parts to strengthen the bow forming part in the directions of the wings thereof and thus prevent drooping of said wings and to wholly 20 conceal the ends of the knot forming part in back of said band forming part.

2. A necktie comprising a bow-forming member; a narrow neckband forming member; and a knot-forming member; each of said members 25 comprising a plurality of plies of fabric material, the bow-forming member having end wings and a reduced connecting portion therebetween; the said knot-forming member being narrow throughout; the neckband forming member being adapted to be disposed in a longitudinal flatwise position in back thereof with its medial portion coincident with the said connecting portion; the said knot-forming member adapted to be placed flatwise in front of the aforesaid connecting portion and at right angles thereto and the ends thereof adapted to be passed over the upper and lower edges of said connecting portion 30 and the corresponding edges of the medial portion of the neckband forming member and knotted in back of the latter so as to transversely curve said connecting portion of the said bow-forming member and said medial portion of the neckband forming member and to coact with the multi-ply structures of these parts to strengthen 35 the bow-forming member in the directions of the wings thereof and thus prevent drooping of said wings, the ends of the knot-forming member being narrower than the ends of the bow-forming member to wholly conceal the ends of the knot-forming member in back of said bow-forming member.

3. A necktie comprising a bow-forming member having a central neck of reduced width, a narrow neckband extending lengthwise of said 55 member along the back of said neck, and a narrow knot-forming member surrounding said neck and band, the latter member being knotted behind said band and having ends which are narrower than the ends of the bow-forming 60 member.
